HUMIDIFIER

Leo Kresser, Springfield, Mass.

Application January 12, 1937, Serial No. 120,153

5 Claims. (Cl. 261—76)

This invention relates to humidifying apparatus, and more particularly to portable apparatus for regulating the moisture content of the atmosphere in homes or in connection with industrial applications which employ materials or processes requiring a definite range of atmospheric humidity for best results. The textile and printing industries are examples of the foregoing.

10 An object of this invention is to provide novel and improved humidifying apparatus which is more efficient in operation and certain in performance.

Another object is to provide a humidifier which 15 is more attractive in appearance and convenient in use.

Another object is to provide a humidifier which is more silent in operation.

Still another object is to provide a humidifier 20 which embodies novel and improved means for vaporizing water.

A further object is to provide a humidifier in which the discharge of water vapor may be varied over wide limits in accordance with demand.

Other objects and advantages will in part be specifically stated and in part be obvious when the following specification is read in connection with the drawings, in which:

30 Fig. 1 is a view in vertical section of the improved humidifier; Fig. 2 is a cut-away view of the interior of the humidifier;

Fig. 3 is a top plan view of the humidifier as seen with the cover removed; Fig. 4 shows the rotary air compressor and a fragmentary portion of the motor in vertical section; Fig. 5 shows an end view of the compressor with the cover plate removed; and Figs. 6 and 7 are enlarged detail views showing the separator which removes oil 40 vapor from the output of the air compressor.

Referring in more detail to Fig. 1, the reference letter K indicates a cabinet which forms a housing for the component parts of the apparatus. At the bottom of the cabinet is a filter chamber F 45 which contains any suitable filtering materials. The chamber has a perforated bottom 1 which leaves a large area for the passage of air, but which will retain the filtering material 2. The chamber F has on two sides extensions 4 which fit slidably into guides 5 which are attached to the bottom part of the cabinet. In the cabinet 50 is mounted on suitable cross members 6, an electric motor M which carries on one side a blower B, and on the other side a rotary air compressor C. The blower consists of a multivane wheel 1

which is mounted on an extension of the motor shaft, and a housing 8 which encloses the wheel. The housing is suitably attached by means of a member 9 to the motor supports 6, and has an opening 10 at the top for the discharge of the 5 air. The air inlet of the blower is adjacent the wheel 7, as best seen in Fig. 2. Below the housing is a water tank W, supported by cross members 12, which are fastened to the cabinet. Any surplus water accumulating in the blower housing 10 10 is drained back to the tank through an opening 14 in the lower part of the blower housing. In the blower housing 8 on the discharge side is attached an atomizer 15 which consists of two nozzles. Nozzle N¹ is vertically positioned and 15 is connected by means of tube 16 to a supply of compressed air which is shown as compressor C. The air issuing from nozzle N¹ strikes a nozzle N² which has a horizontal or slightly inclined position. This nozzle is connected by means of 20 tube 17 to the lower part of the water tank W. The nozzle N² is secured to the atomizer 15 by a threaded connection, and its position is adjustable. In axial alignment with the nozzle N¹ 25 is a tube T which confines the mist of water leaving the atomizer 15 and directs it upwardly. The lower end 18 of tube T is cut at a bias and the strong air flow from the blower B passes upwardly through the tube and entrains the water mist.

30 The rotary air compressor is mounted on the electric motor as shown in Fig. 4. It consists of a compressor block 19 which is fitted onto the endplate 20 of the motor. The shaft 21 carries a rotor 22 which has a number of slots in which 35 blades 23 move freely. The compressor block 19 is mounted eccentrically with the shaft 21 and a crescent shaped space is left between the rotor and the block. This space is partitioned by the blades 23 and when the rotor turns, air is drawn 40 in through openings 24, 24', and 24''. This air is compressed and discharged through opening 25 in the compressor block. In the discharge opening 25, a number of circular baffle plates 26, shown in Fig. 6 and Fig. 7, are mounted and have 45 slots spaced around their circumference. The plates are set on a stem 27 and are separated by washers 30. The slots of the respective plates are arranged in staggered relation and the air passing through the separator is forced to take a 50 tortuous course, and the oil vapors which are suspended in the air are condensed upon the baffle plates. Clean air is discharged through opening 28 (Fig. 5) and a tube 16 is there connected which leads to the atomizer 15, as best 55

seen in Fig. 2. The oil which is deposited upon the baffle plates 26 is drained through outlet 29 and a tube 31 (Fig. 2) to an oil tank O, which contains a supply of lubricating oil for the compressor, and which is secured to the cabinet K in any suitable manner, as by straps. A tube 32 (Fig. 1) leads from the bottom of the oil tank to a connection 33 of the motor endplate (Fig. 4) and an inside duct 34 leads the oil to the bearing and to the compressor blades 23. A humidostat H is mounted in the cabinet in a location such that it is always surrounded by dry air flowing through the cabinet, and automatically controls the motor circuit in accordance with the moisture content of the atmosphere. The housing 8 of the blower B may have a double wall and the space between the walls is preferably filled with suitable sound-absorbing material.

In the operation of the apparatus, the blower B draws air through the filter chamber F and the filter material retains all dust, lint and like impurities suspended in the air. The blower moves the air through the blower housing 8 and discharges it through the outlet 10. A part of this air passes upwardly through tube T. At the same time, the compressor C draws air through openings 24, 24' and 24'' and discharges it under pressure through the baffle plates of the oil separator in the outlet opening 25. The air flows through outlet 28 and tube 16 (Fig. 2) to the nozzle N¹ of the atomizer. At the same time, lubricating oil will be supplied to the compressor by the air pressure communicated through tube 31 to the tank O. The velocity of the air at the nozzle N¹ is very high and when it passes the opening of nozzle N², a vacuum is created therein which draws water through tube 17 from the water tank W. The water at the nozzle N² is broken up into a fine mist by the impact of the air stream issuing from the nozzle N¹. The mist enters tube T and is carried upwardly by the stream of air from the blower. At the exhaust end 10, the mist issues concentrically with the dry air stream from the blower housing 8. The dry air mixes with the mist, completely evaporating it, and the moisture is introduced into the room atmosphere with no expelled droplets to be deposited on nearby articles. As the moisture content of the room atmosphere is raised, the relative humidity eventually reaches the desired value, and the moisture sensitive element in the humidostat expands. The electric switch in the humidostat is opened by the element and operation of the motor M is discontinued. As the relative humidity is lowered again, the sensitive element contracts, the switch is closed and operation of the apparatus is resumed.

It will be obvious that many changes and modifications may be made by anyone skilled in the art without departing from the spirit and scope of the invention as set forth in the following claims;

I claim:—

1. In a humidifier, a source of water, an air compressor, a fan blower, means for driving said compressor and said fan, an air passage having a discharge outlet and extending from said fan to said outlet, a water discharge nozzle positioned in said passage, means for directing a jet of compressed air from said compressor across the end of said water nozzle, and a tubular conduit positioned within said passage in alignment with said jet of compressed air for directing atomized water to said outlet. 5

2. In a humidifier, a source of water, an air compressor, a fan blower, means for driving said compressor and said fan, an air passage having a discharge outlet and extending from said fan to said outlet, means including a jet of compressed air from said compressor for atomizing water within said passage, and a conduit positioned within said passage to receive said atomized water and conduct it to said discharge outlet, said conduit having the inner end thereof shaped to receive air from said blower. 20

3. In a humidifier, a source of water, an air compressor, a fan blower, a single means for driving said compressor and said fan, an air passage having a discharge outlet and extending from said fan to said outlet, means including a compressed air jet from said compressor for atomizing water within said passage, and a conduit positioned within said passage to jointly receive said atomized water and a portion of the air issuing from said blower, said conduit extending from an intermediate portion of said passage to said discharge outlet. 30

4. In a humidifier, a source of water, an air compressor, a fan blower, a single means for driving said compressor and said fan, a spiral air passage having a discharge outlet and extending from said fan to said outlet, means including a compressed air jet from said compressor for atomizing water within said passage, and a conduit positioned within said passage and extending from said discharge outlet to a point adjacent said atomizing means, the inner end of said conduit being shaped to jointly receive atomized 40 water and a portion of the air delivered by said fan. 45

5. In a humidifier, a source of water, an air compressor, a fan blower, a single means for driving said compressor and said fan, a spiral air passage having an upwardly directed discharge outlet and extending from said fan to said outlet, means including a compressed air jet from said compressor for atomizing water within said passage, and a conduit vertically positioned within said passage and extending from said discharge outlet to a point adjacent said atomizing means, the lower end of said conduit being cut on a bias, whereby air from said fan will assist in directing atomized water into said conduit. 50 55 60
